UNITED STATES PATENT OFFICE.

HARRY W. LOWE, OF OMAHA, NEBRASKA, ASSIGNOR, BY MESNE ASSIGNMENTS, TO SPRAGUE CANNING MACHINERY CO., A CORPORATION OF ILLINOIS.

PULPING-MACHINE.

1,262,530.

Specification of Letters Patent. Patented Apr. 9, 1918.

Application filed February 1, 1917. Serial No. 145,875.

To all whom it may concern:

Be it known that I, HARRY W. LOWE, a citizen of the United States, residing at Omaha, in the county of Douglas and State 5 of Nebraska, have invented new and useful Improvements in Pulping-Machines, of which the following is a full, clear, concise, and exact description, reference being had to the accompanying drawing, forming a 10 part of this specification.

My invention relates to pulp machines.

One of the objects of my invention is to provide an improved pulp machine in which means are provided for breaking up the 15 fruit as it is fed into the perforated screen, thereby making the product uniform and preventing injury to the screen.

A further object of my invention is to provide improved mechanism having a 20 safety device for preventing foreign substances from getting into the screen.

A further object of my invention is to provide an improved machine in which the feeding and crushing mechanism is readily 25 accessible for cleaning and repair.

A further object of my invention is to provide an improved pulp machine in which the drier pulp is uniformly mixed with the juicier pulp to insure a uniform product.

10 In the drawings, in which one embodiment of my invention is shown:

Figure 1 is a vertical longitudinal section of a pulp machine embodying my invention.

Fig. 2 is an elevation of the supply end 15 of the pulp machine.

Fig. 3 is a sectional view on the line 3—3 of Fig. 1.

Fig. 4 is a sectional view on the line 4—4 of Fig. 1.

40 Fig. 5 is an enlarged sectional view of the feed worm and driving connection.

Fig. 6 is a perspective view of the feed worm casing.

Referring now to the drawings in detail, 45 the pulp machine comprises an elongated cylindrical headed apertured receptacle 10, a rotary stirrer or agitator 11 for forcing the fruit through the apertures in the receptacle 10; a drain pan 12 which receives the 50 material forced through the apertures in the receptacle 10; an outlet 13 for the discharge of the material which is not forced through the apertures in the receptacle, mechanism 14 for feeding the fruit to the receptacle 10

and breaking it up, driving mechanism 15 55 for the agitator 11 and feed mechanism 14 and a frame 16 for supporting the receptacle 10, driving mechanism 15, etc.

The receptacle 10 comprises a lower semi-cylindrical apertured screen 17 and a semi-cylindrical hood 17^a which can be removed 60 to permit access to the interior of the receptacle, a feed head 18 at one end of the receptacle 10 and a discharge head 19 at the other end of the receptacle.

65 The agitator 11 comprises a plurality of paddles 20 secured to rotatable spiders 21.

The drain pan 12 extends beneath the receptacle and is provided with an outlet 22 and is hinged at one side to the frame 16 70 at 23 and latched to the other side of the frame at 24.

The feed mechanism 14 comprises a worm or screw 25 rotatably mounted in a casing 26, through the apertures 27 of which the 75 fruit is forced into the receptacle 10; the inner end of the casing 26 may be provided with radial ribs 27^a to prevent the fruit from slipping along the end of the casing. The fruit is supplied to the feed mechanism 80 by means of a hopper 28.

The driving mechanism 15 comprises a shaft 29 to which the spiders 21 and worm 25 are secured, mounted in suitable bearings 30 and 31 at the end of the frame 16; a 85 pulley 32 driven from any suitable source of power not shown and any suitable clutch member 33 for connecting and disconnecting the shaft 29 with respect to the pulley 32.

90 The screen 17 has its end edges permanently secured to the heads 18 and 19 and its side edges fixedly secured to the side member 34 of the frame. The hood 17^a is detachably secured in position by means of 95 the eccentric clamps 35 which force the sealing strips 36 into engagement with the laterally extending flanges 37 of the screen 17.

A swinging gate-valve 38 is provided for controlling the discharge through the outlet 13, the gate-valve being mounted to swing on a boss 39 formed integral with the discharge head 19.

100 In order to prevent injury to the machine in case the worm or screw 25 should become jammed, a shear-pin connection 40 is provided between the shaft 29 and the worm 25. This shear-pin connection comprises a col-

lar 41 secured on the shaft 29 by means of a set-screw 42, a collar 43 secured on an extension sleeve 44 of the worm 25 by means of a set-screw 45, and a shear-pin 46, extending through registering openings in the collars 41 and 43.

The outer portion 47 of the casing 26 for the worm is made separate from that portion of the casing which extends within 10 the screen 17, as shown in Fig. 1, and the bracket 48 which supports the bearing 30 is made separate from the frame 16, so that by detaching the bracket 48 from the frame 16 and slipping it off the end of the shaft 29, 15 the outer portion 47 of the hopper, together with the worm 25, may be slipped off the end of the shaft for cleaning, repairing, etc.

The side members 34 are secured at their ends to front and rear supporting members 20 49, 50, respectively, as indicated in Figs. 1 and 2.

The outlet 22 of the drain pan is nearer the discharge head of the pulper. The slope of the drain pan from the discharge end to 25 the outlet 22 is considerably steeper than the slope from the feed end. The reason for this is that the material forced through the screen 17 is juicier at the feed end and drier at the discharge end and the juicier 30 material runs much more freely than the drier material, the juicier material requiring a lesser slope to cause it to flow toward the outlet. As a result of these different slopes of the drain pan, the juicier material 35 is uniformly mixed with the drier material and the result is a uniform product.

Having described my invention, what I claim as new and desire to secure by Letters Patent, is:—

40 1. In a pulp machine, a headed receptacle, an apertured headed cylindrical casing secured adjacent said head; a shaft coaxial with said casing and extending through said casing head; a feed worm in 45 said casing sleeved on such shaft for forcing the fruit through the casing aperture into the receptacle; an agitator in the receptacle for forcing the fruit through the receptacle apertures; a frame for supporting said receptacle and a bearing bracket for said shaft extension detachably secured to said frame whereby when said bearing bracket is removed, said casing and worm may be slipped off from said shaft.

55 2. In a pulp machine, an elongated apertured receptacle, means for supplying fruit, adjacent one end of said receptacle; an agitator operating in said receptacle for forcing the fruit through said aperture; an 60 elongated drain pan located beneath said receptacle, and having an outlet therefrom, near the other end of the receptacle, said drain pan having a surface sloping downwardly from the supply end of the receptacle and having a surface sloping down-

ward from the other end of the receptacle, said second sloping surface, being substantially steeper than the first whereby the drier pulp will be uniformly mixed with the juicier pulp.

3. In a pulp machine a perforated screen, a substantially horizontal rotatable shaft, a sweep secured to said shaft and moved thereby to force the fruit through said screen, and means for breaking up the fruit 75 and supplying it to said screen comprising a feed device coaxial with said shaft and driven thereby, and a casing for said feed device having an aperture through which said feed device squeezes the fruit, the apertured portion of said casing overlying said screen.

4. A fruit-pulping machine comprising a perforated screen, a substantially horizontal shaft, a sweep secured to said shaft for 85 forcing the fruit through the perforations in the screen, means for receiving the pulp forced through said screen, other means for discharging the refuse which is not forced through said perforated screen, and means 90 for breaking up the fruit and supplying it to the perforated screen, comprising a partition surrounding said shaft and lying in a plane substantially perpendicular to said shaft and having an opening therein 95 and means for squeezing the fruit through said opening.

5. A fruit pulping machine comprising a perforated screen, a substantially horizontal shaft, means secured to said shaft for forcing the fruit pulp through said screen, means for receiving the pulp forced through said screen, other means for discharging the refuse which is not forced through said screen, and means for breaking up the fruit 100 and supplying it to the perforated screen comprising a partition through which said shaft extends, lying in a plane substantially perpendicular to said shaft and having an opening therein, and a rotatable helical feed 105 device coaxial with said shaft for squeezing the fruit through the opening in said partition.

6. A fruit-pulping machine comprising a perforated screen, a substantially horizontal shaft, a sweep secured to said shaft for forcing the fruit-pulp through the perforated screen, means for receiving the pulp forced through the screen, other means for discharging the refuse which is not forced 110 through the screen, and means for breaking up the fruit and supplying it to the perforated screen comprising a chamber into which said shaft extends, having an opening therein leading from the chamber to the 115 screen, and a feed device coaxial with said shaft and operating in said chamber for squeezing the fruit through the opening in said chamber to said screen.

7. A fruit-pulping machine comprising a 120

perforated screen, a substantially horizontal shaft, a sweep secured to said shaft for forcing the fruit-pulp through said perforated screen, means for receiving the pulp forced through said screen, other means for discharging the refuse not forced through said screen, and means for breaking up the fruit and supplying it to the perforated screen comprising a chamber into which said shaft

10 extends, having an opening leading from said chamber to said perforated screen, and a helical feed device coaxial with said shaft and operating in said chamber to squeeze the fruit through the opening from said chamber to said perforated screen.

8. A fruit-pulping machine comprising a perforated screen, a substantially horizontal shaft, a sweep secured to said shaft for forcing the fruit through said perforated screen, means for receiving the pulp which is forced through said screen, other means for discharging the refuse which is not forced through said screen, and means for breaking up the fruit and supplying it to the perforated screen comprising a chamber into which said shaft extends, said chamber having a wall lying in a plane substantially perpendicular to said shaft, said wall having a series of openings therein surrounding said

25 shaft, and a screw propeller device secured to said shaft and operating in said chamber to squeeze the fruit through said openings from the chamber to the perforated screen.

9. A fruit pulping machine comprising a perforated screen, a substantially horizontal shaft, a sweep secured to said shaft for forcing the fruit through said screen, means for receiving the pulp forced through said screen, other means for discharging the refuse not forced through said screen, means for breaking up the fruit and supplying it to the perforated screen comprising a chamber through which said shaft extends having openings leading from said chamber to said screen, and a feed device operating in said chamber to squeeze the fruit through said openings to said screen, a chamber having a passage through which fruit is supplied to said screen, said chamber having an opening on its upper side to receive the fruit and having a wall through which said shaft extends, and a bearing for the end of the shaft which extends through said wall.

55 10. A fruit-pulping machine comprising a perforated screen, a substantially horizontal shaft, a sweep secured to said shaft for forcing the fruit through said screen, means for receiving the pulp forced through said screen, other means for discharging the refuse not forced through said screen, means for breaking up the fruit and supplying it to the perforated screen comprising a chamber into which said shaft extends, having an opening leading from the chamber to said

screen, and a feed device coaxial with said shaft and operating in said chamber to squeeze the fruit through said openings to said screen, an upwardly-opening hopper for supplying fruit to said feed device, bearings for said shaft, and a pulley for driving said shaft secured thereto at the end of the shaft which is distant from the hopper.

11. A fruit-pulping machine comprising a cylindrical perforated screen, a substantially horizontal shaft coaxial with said screen, a sweep secured to said shaft for forcing the fruit through said screen, a pan beneath said screen for receiving the pulp forced therethrough, means for discharging the refuse not forced through said screen, and a frame for said machine comprising two end supports, one adjacent each end of said screen, and two side members, one on each side of said screen extending between and secured to said end members, said pan being secured to and supported by said side members.

12. A pulping machine comprising a cylindrical perforated screen, a substantially horizontal shaft coaxial with said screen, a pan underneath said screen for receiving the pulp forced through said screen, means for discharging the refuse not forced through said screen, and a frame for said machine comprising two end supports one at each end of said screen, and two side members one at each side of said machine, and extending between and secured to said end members, said pan and screen being secured to and supported by said side members.

13. A pulping machine comprising a cylindrical screen, a substantially horizontal shaft coaxial with said screen, a sweep secured to said shaft for forcing the fruit through said screen, a pan underneath said screen for receiving the pulp forced through said screen, means for discharging the refuse not forced through said screen, means for breaking up the fruit and supplying it to the perforated screen comprising a chamber into which said shaft extends having an opening from said chamber to said screen, and a feed device operating in said chamber to squeeze the fruit through said opening, and a frame for said machine comprising two end supports one at each end of said screen, and two side members, one at each side of said screen extending between and secured to said end members, said pan being secured to and supported by said side members.

14. A pulping machine comprising a cylindrical screen, a substantially horizontal shaft coaxial with said screen, a sweep secured to said shaft for forcing the fruit through said screen, a pan underneath said screen for receiving the pulp forced through said screen, means for discharging the refuse not forced through said screen, means for breaking up the fruit and supplying it to the

- perforated screen comprising a chamber into which said shaft extends having an opening from said chamber to said screen, and a feed device operating in said chamber to squeeze the fruit through said opening, and a frame for said machine comprising two end supports one at each end of said screen, and two side members one at each side of said screen extending between and secured to said end members, said pan and screen being secured to and supported by said side members.
15. A pulping machine comprising a cylindrical perforated casing, a substantially horizontal shaft coaxial with said casing, a sweep secured to said shaft for forcing the fruit through the perforations in said casing, means for receiving the pulp forced through said perforations, means for discharging the refuse not forced through said perforations, means for breaking up the fruit and supplying it to the perforated screen comprising a chamber into which said shaft extends having an opening from said chamber to said casing, and means operating in said chamber for squeezing the fruit through said opening, said screen comprising two semi-cylindrical portions, and means

for clamping said semi-cylindrical portions together.

16. A pulping machine comprising a cylindrical perforated casing, a substantially horizontal shaft coaxial with said casing, a sweep secured to said shaft for forcing the fruit through the perforations in said casing, means for receiving the pulp forced through said perforations, means for discharging the refuse not forced through said perforations, means for breaking up the fruit and supplying it to the perforated screen comprising a chamber into which said shaft extends, having an opening from said chamber to said casing, and means operating in said chamber for squeezing the fruit through said opening, said screen comprising two semi-cylindrical portions, and means for clamping said semi-cylindrical portions together comprising a plurality of manually-operated levers.

In witness whereof, I have hereunto subscribed my name.

H. W. LOWE.
